UNITED STATES PATENT OFFICE

ISIDOR GOLDBERG, OF NEW YORK, N. Y., ASSIGNOR TO PILOT RADIO AND TUBE CORPORATION, OF NEW YORK, N. Y., A CORPORATION OF DELAWARE

DESIGN FOR A CABINET FOR RADIORECEIVERS

Application filed January 7, 1933. Serial No. 46,759. Term of patent 3½ years.

To all whom it may concern:

Be it known that I, ISIDOR GOLDBERG, a citizen of the United States, residing in the city of New York, with a post-office address in care of the Pilot Radio and Tube Corporation, No. 521 Fifth Avenue, borough of Manhattan, city and State of New York, have invented a new, original, and ornamental Design for a

Cabinet for Radioreceivers, of which the following is a specification, reference being had to the accompanying drawing, forming part thereof.

I claim:

The ornamental design for a cabinet for radioreceivers, as shown.

ISIDOR GOLDBERG.
